UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL STOVE.

Application filed July 3, 1919. Serial No. 308,542.

To all whom it may concern:

Be it known that I, RUDOLPH HOFFMAN, a citizen of the United States, residing at Kankakee, in the county of Kankakee and State of Illinois, have invented certain new and useful Improvements in Oil Stoves, of which the following is a specification.

My invention relates to oil stoves of the type embodying a constant level oil supply reservoir and one or more burners mounted for vertical movement with reference to such constant level whereby to control the supply of oil thereto; and the invention has especial reference to the means providing an extensible pipe connection between a stationary supply pipe and the burners, and to the raising and lowering means for the burners.

In prior structures of the character stated, difficulty has been encountered in providing an extensible pipe connection capable of effectively preventing the escape of oil, the packing gland usually employed between the two telescoping pipe sections having been found inadequate for properly sealing the sliding joint therebetween by reason of the tendency of the oil to creep by capillary attraction past the packing, especially when the latter has become slightly worn in use.

The principal object of this invention is to provide a novel method of sealing the joint between the two telescoping sections which will absolutely prevent the escape of oil.

The foregoing object of the invention is accomplished by the provision of a mercury seal between the relatively movable pipe sections; and a further object of the invention is to provide means for effectively preventing the leakage of the mercury employed while the stove is being shipped and under similar situations.

Another object of the invention is to provide improved means for effecting the raising and lowering movements of the burner proper, which is permitted by the telescoping pipe sections.

The objects of the invention thus generally stated together with other and ancillary advantages may be attained by the construction and arrangement illustrated in the accompanying drawings forming part hereof, in which Figure 1 is a fragmentary side elevation of a stove embodying the features

of my invention. Fig. 2 is a fragmentary horizontal section on line 2-2 of Fig. 3. Fig. 3 is a vertical sectional view taken in the plane of line 3-3 of Fig. 1. Fig. 4 is a fragmentary vertical section taken on the line 4-4 of Fig. 5. Fig. 5 is a fragmentary horizontal section taken on line 5-5 of Fig. 4. Fig. 6 is a fragmentary vertical section taken on 6-6 of Fig. 3.

In the drawings, 1 indicates a stove frame having supported at one end thereof an oil supply tank 2 communicating in a well-known manner with a constant level oil receptacle or well 3, also supported by the frame 1. 4 is the main oil delivery pipe for the stove leading from the well 3, and comprising an upright portion and a horizontal portion stationarily mounted upon the stove frame. 5 designates generally a burner having an oil receptacle 6 commonly termed a burner bowl or trough which is adapted to be connected to the main delivery pipe 4 by means of an extensible pipe connection 7. Means including a hand wheel are adapted to effect the raising and lowering movements of the burner relative to the well 3.

The oil supply tank 2, well 3 and delivery pipe 4 may be of any suitable and well-known construction and arrangement, as may also be the burner 5 with its oil trough 6. It is therefore deemed unnecessary to illustrate and describe these parts in detail.

The extensible connection 7 between the burner bowl or trough 6 of the burner and the main delivery pipe 4 comprises two sections 7^a and 7^b carried respectively by the pipe 4 and trough 6. The section 7^a is made of a diameter slightly less than the diameter of the section 7^b and at its lower end is screw-threaded into a fitting 8 connected in a well-known manner to the delivery pipe 4 so as to communicate therewith. The pipe section 7^b is rigid with the lower edge of the burner bowl 6, being secured thereto as by brazing, and is adapted to freely receive the section 7^a.

The means for clamping the fitting 8 upon the delivery pipe 4 so that it shall be capable of firmly supporting the burner in its proper position, comprises a pair of links 9 and 10 having laterally extending portions 11 and 12 at their upper ends adapted to cooperatively engage with the upper end of the fitting 8, and at the lower

ends of said links is a block 13 fixed with reference thereto and having a set screw 14 therein adapted to operatively engage with the pipe 4. To prevent a torsional movement of the fitting 8 with reference to the links 9 and 10, the horizontal portions 11 and 12 of said links are apertured to receive the extensible pipe 7, and the links are provided in their sides with slots 15 adapted to receive studs 15^a on the sides of the fitting. It will be seen that by tightening the screw 14, the fitting 8 may be drawn downwardly onto the delivery pipe 4 and firmly clamped in position thereon, the slots 15 in the links permitting relative movement of the studs therein in this operation.

For the purpose of providing an annular channel around the inner pipe section 7^a of the extensible delivery pipe, for the reception of a quantity of mercury in which the lower end of the pipe section 7^a may be immersed, I provide a tubular stem or member 16 carried by the fitting 8. This member is in the form of a pipe of a diameter somewhat greater than the diameter of the pipe section 7^b and at its lower end is threaded into a socket 17 provided in the upper portion of the fitting 8. The pipe section 7^a and the tubular member 16 are thus concentrically arranged and are spaced apart to form a channel 18. Said channel is of sufficient width to provide spaces upon opposite sides of the pipe section 7^b which at the lower ends thereof are filled with a sealing liquid such as mercury 19. It will be seen that oil standing in the pipe section 7^a and overflowing into the space between it and the section 7^b is prevented from flowing around the lower end 40 of the section 7^b by the mercury in the channel into which said section extends.

The means for raising and lowering the burner comprises a rotary member or nut 20 having secured on its under side a hand wheel 21, and being threaded upon the upper portion of the tubular member 16. Rising from said nut are a pair of spring arms 20^a having at their upper ends clamping members 22 adapted to engage with a collar 23 fixed on the outer periphery of the pipe section 7^b. It will be seen that when it is desired to remove the burner from the stove it is only necessary to disengage the clamping members 22 from the collar 23 against the action of the spring arms 20^a. Normally, however, the upward movement of the burner is limited by means to be directly described, to prevent the withdrawal of the lower end of the outer pipe section 7^b from the mercury in the channel 18, a sufficient quantity of mercury being provided to cover the lower end of said movable pipe section when it is in its uppermost position.

65 The means for limiting the upward move-

ment of the nut 20 and thereby of the burner, comprises a spider 24 mounted upon the under side of the hand wheel 21 and having a central ring 25 apertured to receive the tubular member 16; and fixed with reference to said tubular member is a stop member 26 having at its upper end a laterally projecting lug 27 adapted to be engaged by the upper surface of the ring 25 in the operation of the wheel upwardly relative to the tubular member 16. Said stop member may be flanged outwardly at its lower end so as to extend between the free end of the horizontal portion 12 of the link 10 and the horizontal portion 11 of the link 9 and then downwardly between the fitting 8 and the link 9. By this construction, the stop member is clamped in position by the means for fastening the fitting 8 upon the horizontal portion of the pipe 4.

In the normal or operative position of the parts, it will be seen that the annular channel 18 formed between the tubular member 16 and the inner pipe section 7^a is open at its upper end. For effectively closing said channel when the stove is to be shipped or transported from one place to another and thus prevent the leakage of mercury therefrom, I provide means carried by the pipe section 7^b and movable into closing position by means of the raising and lowering means. Such closing means comprises an annular valve member 28 on the outer periphery of the pipe section 7^b; and an annular valve member 29 fixed on the inner periphery of the pipe section 7^b. Herein the annular valve member 28 on the outer periphery of said pipe section is formed integral with the collar 23, and both of said members are beveled at their lower ends as at 30 and 30^a and are adapted to be drawn downwardly into engagement with inclined seats formed upon the upper ends of the pipe section 7^a and tubular member 16, by an operation of the hand wheel 21. It will be seen that said members after being forced into snug engagement with the pipe section and tubular member, will be held in such position by the frictional engagement of the nut 20 with the screw threads on the periphery of the tubular member as well as of the clamping members 22 with the collar 23.

For the purpose of indicating to the user the proper positions for the burner in use, the stop member 26 may be provided on its forward face with a scale having suitable legends thereon, such as "Out," "Medium" and "Light" (Fig. 6). When the ring 25 of the spider 24 becomes positioned opposite these marks, in the raising and lowering operation of the burner, they will indicate respectively, that the burner trough has been raised above the constant oil level, that the trough has been raised to a midway position with its upper portion above the oil level,

or that the trough is in its lowermost position with its upper edge just above the oil level, as shown in Fig. 3. The movement of the trough 6 below the constant oil level is prevented by the annular members 28 and 29 engaging with their seats upon the upper ends of the pipe section 7^a and the tubular member 16. These annular members are, however, only drawn down tightly upon their seats when the stove is to be moved, so as to prevent the escape or leakage of the mercury if the stove is tipped upon end or inverted in the moving operation.

Suitable means may be provided for guiding the burner in its vertical movements, preventing a rotation of the pipe section 7^b relative to the tubular member 16 as the hand wheel is rotated. Herein such means comprises a rod 31 fixed upon the inner side 20 of the trough 6 of the burner and depending through an aperture 32 in a laterally projecting member 33. Said laterally projecting member 33 is herein shown as being formed integral with the horizontal portion 25 11 of the link 9.

It will be seen that I have provided an efficient extensible pipe connection for oil stoves embodying vertically movable burners. It is of comparatively simple construction and the seal is of such character that it will not become worn or inefficient. Moreover the valve members 28 and 29 when forced upon their seats effectively prevent the escape of the mercury when the stove 30 is inverted as in shipment in spite of the difficulty commonly experienced in effectively preventing a leakage of mercury owing to its high specific gravity. It is also to be noted that the raising and lowering means is of such character that a rapid lowering of the burner becomes impossible, such rapid lowering being objectionable because of the tendency of the oil in the inner pipe section 7^a to be forced upwardly into the bowl 6 and overflow.

While I have herein described the invention with considerable particularity, it will be understood that I do not intend that the appended claims shall be limited in the interpretation thereof except as may be necessitated by the state of the prior art.

For example, I have found that in some instances instead of raising and lowering the burner it is desirable to stationarily support the burner bowl and control the height of the flame by raising and lowering the oil well or receptacle which communicates with the supply tank. Such an arrangement constitutes a reversal of that herein disclosed.

In a co-pending application, Serial No. 540,744, filed March 3, 1922, I have shown and described a raising and lowering means substantially similar to that herein disclosed, in connection with a preferred embodiment of the invention, and in compliance with

the statute, I am claiming said means broadly in said application.

I claim as my invention:

1. An oil stove comprising, in combination, with a constant level oil supply reservoir, a main delivery pipe and an oil burner including a trough, an extensible pipe connection comprising an inner stationary pipe section communicating at its lower end with said delivery pipe, an outer or movable pipe section fixed with reference to said trough and communicating therewith and of greater diameter than the inner section so as to loosely receive the latter, a tubular member forming with said inner section an annular channel for the reception of a quantity of mercury into which the lower end of the outer pipe section is adapted to be immersed, means for raising and lowering the trough, and means on said movable pipe section adapted to engage with said tubular member and the inner pipe section to close said annular channel. 75

2. An oil stove comprising, in combination, with a constant level oil supply reservoir and a burner comprising a vertically movable trough, means for conducting oil from said reservoir to said trough including two relatively stationary pipe sections spaced apart to form an annular channel therebetween for the reception of a quantity of mercury, and a relatively movable pipe section the lower end of which is adapted to be immersed in said mercury, and means for moving the burner and said movable pipe section relative to said reservoir. 90

3. An oil stove comprising, in combination with a constant-level oil supply reservoir having a horizontal delivery pipe, and a burner movable vertically relative to said pipe, means for conducting a supply of oil from said delivery pipe to said burner comprising two concentric pipe sections spaced apart to form a channel for receiving a quantity of mercury the inner pipe section communicating with said delivery pipe, a relatively movable pipe section fixed with reference to said burner and communicating therewith and having its lower end depending into said channel and arranged to be immersed in said mercury, and means on said movable pipe section adapted to close said channel. 110

4. An oil stove comprising, in combination with a constant-level oil supply reservoir, a delivery pipe and a burner vertically movable relative to said reservoir, means for conducting a supply of oil from said delivery pipe to said burner comprising a fitting mounted on said delivery pipe and communicating therewith, a pair of pipes screw-threaded into said fitting and mounted in spaced relation so as to form an annular channel therewith, the inner one of said 125

1 pipes communicating through said fitting with the delivery pipe, and a relatively movable pipe section fixed with reference to said burner and communicating therewith 5 and the inner one of said first-mentioned pipes, said movable pipe section being adapted to depend into said annular channel, and a sealing liquid in said channel in which the lower end of said movable pipe 10 section is immersed.

5. An oil stove comprising, in combination with a constant-level oil supply reservoir, a delivery pipe and a vertically movable burner, means for conducting a supply 15 of oil from said delivery pipe to said burner comprising a fitting clamped on the delivery pipe and communicating therewith, a pair of concentric sections mounted at their lower ends in said fitting in spaced relation 20 so as to form an annular channel therebetween, a movable pipe section fixed with reference to said burner and adapted to depend into said channel around said inner pipe section, said inner pipe section communicating through said movable pipe section with said burner, means comprising a 25 pair of annular members at the upper end of said movable pipe section adapted to engage with the upper ends of said stationary pipe 30 sections to close said annular channel, and a metallic liquid in said annular channel into which the lower end of said movable pipe section may be immersed.

6. An oil stove comprising, in combination 35 with a constant-level oil supply reservoir, a delivery pipe and a burner movable vertically with reference to said reservoir, a fitting on said delivery pipe, a pair of spaced concentric pipe sections rising from said 40 fitting and forming a channel therebetween, a movable pipe section fixed with reference to said burner and having its lower end entered in said channel, said channel being adapted to receive a quantity of metallic 45 liquid to provide a seal between the stationary inner pipe section and said movable pipe section, the last mentioned pipe sections being arranged to communicate at their 50 opposite ends with the delivery pipe and burner respectively, and means for raising and lowering said burner comprising a rotatable member threaded onto the outer stationary pipe section and having a sliding connection in a circumferential direction 55 only with the movable pipe section.

7. An oil stove comprising, in combination 60 with a constant-level oil supply reservoir, a delivery pipe and a burner movable vertically with reference to said reservoir, a fitting on said delivery pipe, a pair of spaced concentric pipe sections rising from said fitting and forming a channel therebetween, a movable pipe section fixed with reference to said burner and having its 65 lower end entered in said channel, said

channel being adapted to receive a quantity of metallic liquid to provide a seal between the stationary inner pipe section and said movable pipe section, the last mentioned pipe sections being arranged to communicate at 70 their opposite ends with the delivery pipe and burner respectively, and means for raising and lowering said burner comprising a rotatable member threaded onto the outer stationary pipe section and having a sliding connection in a circumferential direction 75 only with the movable pipe section, and means on said movable section adapted to close the channel formed by the stationary 80 pipe sections.

8. An oil stove comprising, in combination with a constant-level oil supply reservoir, a delivery pipe and a burner, an extensible pipe connection between said burner and said delivery pipe including two telescoping pipe sections having a metallic liquid seal therebetween, means for raising and lowering said burner relative to said reservoir comprising a stationary tubular member, a 85 rotary member threaded on said tubular member and operatively connected with the burner, and means for limiting the upward movement of said burner.

9. An oil stove comprising, in combination with a constant-level oil supply reservoir, a delivery pipe and a burner, an extensible pipe connection between said delivery pipe and said burner including an inner stationary pipe section and an outer relatively movable pipe section, said pipe sections communicating respectively with said delivery pipe and said burner, and means for raising and lowering said burner comprising a tubular member encircling the outer pipe section, a rotary member threaded on said tubular member and operatively engaging said relatively movable pipe section, and means for preventing the rotation of said burner and the movable pipe section thereon.

10. The combination of a horizontal delivery pipe, a burner, an extensible pipe connection between said delivery pipe and said burner including an inner pipe section communicating with said delivery pipe, an outer pipe section communicating with said burner and movable therewith, a stationary upright member, and a rotary member threaded on said stationary member and operatively engaging with said burner to move it.

11. The combination of a horizontal delivery pipe, a burner, an extensible pipe connection between said delivery pipe and said burner, a stationary upright stem, a collar fixed with reference to said burner, a rotary member threaded on said stem and having means slidably engaging with said collar for circumferential movement only, and a hand wheel for rotating said rotary member.

12. The combination of a horizontal delivery pipe, a burner, a fitting on said pipe

- and communicating therewith, means for clamping said fitting on said pipe including a pair of links fixed with reference to said fitting and depending on opposite sides of 5 said pipe, a block clamped between the lower end of said links, a clamp screw threaded in said block and adapted to engage said pipe, extensible means for conducting a supply of oil from said delivery pipe to said burner, 10 and means encircling the extensible means imparting up and down movement to said burner.
13. The combination of a horizontal delivery pipe, a burner, means for imparting 15 up and down movements to said burner, an extensible pipe connection between said pipe and burner comprising a stationary pipe section communicating with said delivery pipe, a movable pipe section communicating 20 openly with said burner, and means forming an annular channel with said stationary pipe section adapted to receive mercury or the like in which the lower end of said movable pipe section may be immersed.
- 25 14. The combination of a horizontal delivery pipe, a burner, means for raising and lowering said burner, an extensible pipe connection between said delivery pipe and burner comprising a stationary pipe section 30 communicating with said delivery pipe, a movable pipe section communicating with said burner, means forming an annular channel with said stationary pipe section adapted to receive mercury or the like in 35 which the lower end of said movable pipe section may be immersed, and means actuated by said raising and lowering means for closing the upper end of said channel.
15. In an oil stove, the combination of an 40 oil supply pipe, a burner including a trough, means for raising and lowering the burner, an extensible pipe connection establishing unrestricted communication between said delivery pipe and said trough including two 45 telescoping pipe sections, and means providing a metallic liquid seal between said pipe sections.
16. In an oil stove, the combination of an 50 oil supply pipe, a burner including a trough, means for raising and lowering the burner, an extensible pipe connection between said delivery pipe and said trough including two telescoping pipe sections, means providing a metallic liquid seal between said pipe sections, and means forming a closure for retaining said liquid when the stove is inverted.
- 55 17. An oil stove comprising, in combination, a delivery pipe, a burner including a burner bowl, means for raising and lowering the burner, an extensible pipe connection including a pair of telescoping pipe sections for conducting a supply of oil from said supply pipe to said burner bowl, means 60 providing a mercury seal for the sliding 65 connection between said pipe sections and means for preventing the escape of the mercury when the stove is inverted.
18. The combination with a vertically movable burner, of means for guiding the 70 burner for up and down movement including an extensible pipe connection, and raising and lowering means comprising a collar fixed with reference to said burner, a stationary upright stem, a rotary member threaded on said stem and having a pair of spring arms provided with means for slidably engaging said collar for movement circumferentially thereof only.
19. The combination with a vertically 75 movable burner, of means for conducting a supply of oil to the burner comprising a pair of telescoping pipe sections and a tubular stem providing a channel for the reception of a quantity of mercury and adapted 80 to receive the outer pipe section with its end immersed in said mercury; raising and lowering means for said burner including a member threaded on said stem, a collar fixed on the outer pipe section, means on 85 said threaded member adapted to slidably clamp said collar and means for rotating said threaded member; and means actuated by said raising and lowering means for closing said annular channel, including an annular member fixed on said outer pipe section.
20. In an oil stove, the combination with 90 an oil supply pipe and a vertically movable burner, of an extensible pipe connection establishing open communication between said pipe and said burner, comprising a pair of telescoping pipe sections, and means for providing a seal of mercury or the like between said pipe sections.
21. In an oil stove, the combination with 95 a source of oil supply and a vertically movable burner of an extensible pipe connection between said source of oil supply and said burner comprising a pair of telescoping pipe sections, and means providing a liquid seal of mercury or the like between 100 said pipe sections, raising and lowering means for the burner, and means actuated by the raising and lowering means to form 105 a closure for retaining liquid when the stove is inverted.
22. In an oil stove, the combination with 110 a source of oil supply and a vertically movable burner, of an extensible pipe connection between said source of oil supply and said burner comprising a pair of telescoping pipe sections, raising and lowering means for the burner, and means carried by 115 one of said pipe sections and movable by said raising and lowering means into engagement with the other pipe section to close the annular space therebetween.
23. In an oil stove, the combination with 120 a source of oil supply and a vertically mov-

- able burner, of an extensible pipe connection between said source of oil supply and said burner comprising two concentric stationary pipe sections spaced apart, and a movable pipe section adapted to enter the annular space between the stationary pipe sections, and means on said movable pipe section movable into engagement with the stationary pipe sections to close said annular space.
10. 24. In an oil stove, the combination with a source of oil supply and a vertically movable burner, of an extensible pipe connection between said source of supply and said burner comprising a pair of telescoping pipe sections, means providing a seal of mercury or the like between said pipe sections, raising and lowering means for said burner comprising a stem and a rotary member threaded on said stem and operatively engaging with said burner to move it when the member is rotated, and means actuated in the movements of said burner by said raising and lowering means to form a closure for retaining said mercury.
15. 25. In an oil stove, the combination with a burner and an oil supply pipe mounted for movement relative to each other, of an extensible pipe connection establishing open communication between said burner and said supply pipe comprising two relatively movable sections, and means providing a liquid seal of mercury or the like between said movable sections.
20. 26. An oil stove having a burner, and a feed-pipe for oil, extensible to permit of the vertical movements of the burner, said pipe comprising two telescoping sections respectively communicating with the burner and a source of oil supply, and means providing a metallic liquid seal between said pipe sections and adapted to form a closed chamber for retaining the sealing liquid against escape.
25. 27. An oil stove having a burner, and a feed-pipe for supplying oil to the burner, said pipe being extensible to permit of the vertical movements of the burner and comprising an inner pipe section communicating with a source of oil supply and an outer pipe section communicating with the burner, and means operable by a movement of the outer pipe section into association with the other pipe section whereby to tightly seal the joint therebetween.
30. 28. An oil stove having a burner, and a feed-pipe for oil extensible to permit of the vertical movements of the burner, said pipe comprising a pair of telescoping pipe sections, an upright member rigid with one of said sections, means movable with the outermost pipe section into association with the other pipe section whereby to tightly seal the joint therebetween, and means for moving said movable pipe section comprising a member screw-threaded on to said upright member and operatively associated with the movable pipe section.
35. 29. An oil stove having, in combination, a burner, an oil feed-pipe extensible to permit of the vertical movements of the burner, said pipe comprising two telescoping sections having a sliding joint therebetween, means for sealing the joint during the relative movement of the pipe sections, and additional means providing a seal between the sections when the burner is in its lowermost position.
40. 30. An oil stove having an oil feed-pipe comprising a pair of pipe sections spaced apart to form an annular channel, and means operatively associated with the pipe sections so as to be capable of closing said channel.
45. 31. In an oil stove, the combination of a pair of pipe sections spaced apart to form an annular channel, a third pipe section extending into said channel, and means rigid with the third pipe section and movable into operative association with the first-mentioned pipe sections whereby to close said channel.
50. 32. An oil stove having in combination with a source of oil supply, a pipe formed in two sections having a sliding joint therebetween, and means providing a channel for receiving a quantity of mercury or the like and open at its upper end to receive the outermost pipe section for the immersion of the latter in the mercury.
55. 33. In an oil stove, the combination with a vertically movable burner and a feed pipe, of an extensible pipe connection between the burner and feed pipe comprising an inner pipe section communicating with the feed pipe and an outer pipe section communicating with the burner, and a third pipe section associated with the inner pipe section to form an annular channel adapted to receive a quantity of mercury or the like, and means movable with the outer pipe section into operative association with both of the stationary pipe sections simultaneously whereby to close the upper end of said channel.
60. 34. In an oil stove, the combination with a vertically movable burner and a stationary feed pipe, of an extensible connection between the burner and feed pipe comprising a fitting and two stationary concentric pipe sections mounted therein in spaced relation so as to form an annular channel, and a third pipe section communicating with the burner, said channel being normally open at its upper end to permit the entrance of the third pipe section into the channel and being also adapted to receive a quantity of mercury or the like in which the lower end of the third pipe section may be immersed.
65. 35. In an oil stove, two parts operatively associated so as to form a conductor for oil, said parts having a sliding joint there-

between, and means providing a seal for said joint adapted to prevent the escape of oil by capillary attraction, said means comprising a chamber formed at the joint and having a quantity of mercury or the like therein.

36. In an oil stove, the combination with a burner bowl, means including an extensible pipe-connection for maintaining a constant oil level while permitting the up and down movements of the bowl, and means for raising and lowering the burner bowl with reference to said oil level comprising a part rigid with the bowl, a stationary support, an upright member on said support and a rotary member operatively engaging said upright member and said part whereby in the rotation of said rotary member the burner bowl is caused to move up or down and means for holding the bowl against rotating.

37. In an oil stove, the combination of a burner bowl, means including an extensible pipe connection for maintaining a constant oil level, and means for raising and lowering the burner bowl with reference to said oil level comprising a part depending from the bowl, an upright stationary part with which the first part is operatively associated, means operatively connecting said parts including a member mounted coaxially of the second part and adapted when rotated to cause the burner bowl to move up and down, and means for preventing relative rotation between the parts of the pipe connection.

38. The combination of an oil burner, means for maintaining a constant oil level including a stationary feed pipe, an extensible pipe connection between the burner bowl and said feed pipe comprising a pair of telescoping pipe sections, and means operatively associated with said pipe sections including a member mounted on an upright axis and adapted when rotated to impart a raising or lowering movement to the burner bowl.

39. The combination of an oil burner having a burner bowl, means for maintaining a constant oil level including a pair of telescoping pipe sections, and means for raising

and lowering the burner bowl with reference to said oil level comprising a part rigid with the burner bowl, a stationary upright member and a rotary member operatively connecting said part and said upright member in coaxial relationship and adapted when rotated to impart an up and down movement to the burner bowl.

40. The combination of a burner bowl, means for maintaining a constant oil level including a pair of telescoping pipe sections freely slideable with respect to each other, and means for sealing the sliding joint between said sections including a chamber having therein a quantity of mercury in which one end of one of said pipe sections is immersed.

41. The combination of an oil burner having an annular trough, means for maintaining a constant oil level, and means for raising and lowering said trough with reference to said oil level, the first mentioned means comprising an extensible oil conductor having two relatively slideable pipe sections, and means for supporting a quantity of mercury or the like in which the free end of the outer pipe section is immersed whereby to provide a seal against the leakage of oil from the conductor.

42. In an oil stove, a conductor for oil comprising two relatively slideable telescoping pipe sections, and means providing a seal to prevent the leakage of oil by capillary attraction from the conductor by way of the sliding joint between said pipe sections, said means including a chamber for supporting a quantity of mercury or the like in which the free end of the outer telescoping pipe section is immersed.

43. An oil stove having, in combination, a vertical tubular member, a hand wheel having a screw thread connection with said member, a burner, a rotatable connection between the burner and the hand wheel, and means including a part depending from the burner to prevent the burner from turning.

In testimony whereof, I have hereunto set my hand.

RUDOLPH HOFFMAN.
